UNITED STATES PATENT OFFICE.

JOHANNES EHRCKE, OF SCHÖNEBERG, GERMANY.

WINDOW.

SPECIFICATION forming part of Letters Patent No. 550,124, dated November 19, 1895.

Application filed May 7, 1894. Serial No. 510,273. (No model.)

To all whom it may concern:

Be it known that I, JOHANNES EHRCKE, joiner, of Schöneberg, near Berlin, in the Kingdom of Prussia and German Empire, have invented new and useful Improvements in Windows Adapted to be Closed in an Air-Tight Manner, of which the following is a specification, reference being had therein to the accompanying drawings.

10 The primary object of my invention is to provide simple, effective, and convenient means for making windows, and particularly sliding windows, air-tight when closed. To this end I, in accordance with my invention, 15 provide novel means for mounting the sashes to slide in the jambs and for tightly closing the sashes between the jambs, as well as the joints between the meeting-rails of the sashes and between the end rails of the sashes and 20 the ends of the window-frame.

I also include in my invention novel means for excluding dust, &c., from the window when partly or wholly opened and for raising and lowering the sashes.

25 In order that my invention may be clearly ascertained, I shall first describe in detail the mode in which I carry my invention into practice, and then more particularly point out the invention in the claims.

30 Reference is to be had to the accompanying drawings, forming part of this specification, in which the same parts are designated by like letters in all the figures.

Figure 1 is a front elevation of a sliding window provided with my invention. Fig. 2 is a detail front elevation of one side of the same, parts being removed to disclose the construction. Fig. 3 is a sectional elevation on the line $x-x$, Fig. 1. Figs. 4, 5, 6, and 7 are detail views of the movable jamb and the device for operating the same. Fig. 8 is a sectional plan view of the aforesaid window.

In the form of my invention herein shown 35 I have shown upper and lower sash-frames n and n' , respectively, mounted to slide in a window-frame A. To effectually seal the joints between the sashes n and n' and the jambs, I make, by preference, the jamb h on one side of the window stationary, and the jamb h' on 40 the other side of the window to slide laterally in the frame A to and from the sashes, and I form on the face of said jambs h and h' lon-

gitudinal ribs A', by preference, of the cross-section of a saw-tooth, as shown, and I form the side rails of the sash-frames n and n' with correspondingly-longitudinal grooves B to fit and slide on the ribs A'. I further form the movable jamb h with laterally-beveled cam projections g, as best shown in Figs. 4 and 5, and laterally-beveled slots m in its face, 55 and I mount at the side of said jamb a vertically-sliding bar d, provided with laterally-beveled slots f, cut through its back to engage the aforesaid cam projections g, and with laterally-beveled tongues l to enter the slots m 60 in the face of the jamb, and projections b to ride in slots in the cover D of the frame A and guide said bar d in its movement. Thus by moving the cam-bar d vertically the beveled faces of the slots f therein will, through 65 the cam projections g, cause the jamb h to be pressed tightly against the sides of the sashes and said sashes to be pressed tightly against the fixed jamb h' , so as to tightly close the joints between said jambs and the sashes. 70 For thus working the cam-bar d vertically I provide the same with a vertical slot C, and I mount in the cover D of the frame over said cam-bar d a pivotal eccentric E, having a handle i, which eccentric enters the slot C, 75 and when operated by the handle i will operate the cam-bar d, as required.

To seal the joints between the meeting-rails of the sashes n and n' , I provide said rails with reversely-facing angle-flanges H and I, 80 respectively, which when the sashes are closed will interlock and bind the meeting-rails together.

To seal the joints between the end rails of the sashes and the ends of the frame A, I provide, in connection with the lower rail of the lower sash only, as shown in Fig. 3, an angle-flange J to enter a corresponding longitudinal groove formed in the said lower rail when closed, as shown.

95 For excluding dust, &c., when the sash is open, I provide, as shown herein in connection with the upper sash only, a double screen or two screens L, of wire-gauze or other suitable material, attached to the forward and rear edges of the upper sash n and extending upward to a roller M, mounted and covered within the upper end of the window-frame, so that when the upper sash is lowered the 100

said double screen will be unrolled in accordance therewith and protect the opening of the window.

As a convenient means for rolling up said screen and thus closing the uppersash, which is or is not counterbalanced by weights in the usual manner, I wind on the end of said roller within the end of the frame a cord or wire O to be carried forward through an opening in the cover of said frame over a suitable guide and downward to a fastening device P, whereby said screen and upper sash can be lowered and raised, as shown.

I have shown the sashes herein provided with horizontally-swinging sections o merely as an illustration of one form of window.

Having thus described my invention, what I claim, and desire to secure by Letters Patent, is—

1. In a sliding window, the combination, with the sash frame, of a laterally sliding jamb having beveled lateral projections, and a vertically sliding jamb-operating bar having laterally beveled slots cut through its back to receive said projections and means for engaging the jamb-operating bar to actuate the same.
2. In a window, the combination with the sash frame, of a laterally sliding jamb having beveled lateral cam projections and laterally beveled slots in its face, and a verti-

cally sliding jamb-operating bar having laterally beveled slots to receive said cam projections, and beveled lateral guide tongues to fit the slots in the said jamb and means for engaging the jamb-operating bar to actuate the same.

3. The combination, with the window frame, and its cover D the laterally sliding jamb, and the vertically sliding jamb-operating cam-bar, formed with a vertical slot, of a handled eccentric pivoted in the cover of said frame and entering said vertical slot.

4. The combination, with the window frame and the uppersash working vertically therein, of a screen attached to the upper edge of the upper sash, a blind roller having an end drum within the upper end of the frame on which roller the screen winds, a sash counterbalance connected to said roller, and a cord winding on the drum on the end of said roller reversely to the screen, and leading outward through the front of the frame, whereby on drawing said cord the sash and the screen may be raised to any desired extent, substantially as set forth.

In witness whereof I have hereunto set my hand in presence of two witnesses.

JOHANNES EHLRCKE.
